UNITED STATES PATENT OFFICE.

RICHARD M. BECKER, OF NEW YORK, N. Y., ASSIGNEE TO JOHN THOMAS UNDERWOOD,
OF BROOKLYN, NEW YORK.

COMBINED TYPE-WRITING AND COMPUTING MACHINE.

1,104,468.

Specification of Letters Patent. Patented July 21, 1914.

Application filed April 2, 1913. Serial No. 759,880.

To all whom it may concern:

Be it known that I, RICHARD M. BECKER, a citizen of the United States, residing in Brooklyn borough, in the county of Kings, 5 city and State of New York, have invented certain new and useful Improvements in Combined Type-Writing and Computing Machines, of which the following is a specification.

10 My invention relates to combined type-writing and computing machines.

One object of my invention is to enable the ordinary keys of a typewriter (in such a machine) to be operated at any time for any 15 purpose while at the same time the type of the typewriter are prevented from printing. It is preferable in bringing about this result to alter the touch on the typewriter keys as little as possible. To bring about this result, the keys of the typewriter may operate 20 as ordinarily, but a stop is interposed which arrests the type-bars almost at the printing point, yet before they come so close as to make an impress on the paper.

25 In order to modify the touch of the typewriter (in such a machine) as little as possible, the stop for arresting the type bars is preferably padded, and it arrests said bars at a point where the type cannot strike the stop. Thus it is impossible for the type 30 themselves to be injured by striking the stop.

Other features and advantages will hereinafter appear.

35 In the accompanying drawings, Figure 1 is a plan view of an Underwood-Hanson combined typewriting and adding machine, showing my invention as applied thereto, with most of the parts removed for the sake 40 of simplicity. Fig. 2 is a similar sectional side view. Fig. 3 is a detail of the key which prevents the typewriter type from printing. Fig. 4 is a skeleton perspective view showing the connection between the key 45 which prevents the printing and the stop which arrests the type-bars.

In the Underwood typewriting machine as is usual, keys 1 on key levers 2 swing bell cranks 3 so as to cause type-bars 4 pivoted 50 in a segment 5 to swing upwardly and rearwardly against a platen 6, which platen is adapted to hold the work-sheet. As said type-bars approach the platen, they enter a guide 8 which holds the type 7 against

lateral displacement. As the type approaches the platen, heels 9 on the type-bars 4 strike a universal bar 10 by connections (not shown herein) to operate an escape- 55 ment mechanism for said platen.

The machine herein illustrated is a com- 60 bined type-writing and computing machine of the Underwood-Hanson type in which pendants 11 on the numeral key levers strike bell cranks 12 so as to set up on mechanism (not shown herein) the numbers represented 65 by the numeral keys struck.

If it is desired to set up numbers without printing said numbers on the platen 6, a non-print key 13 may be depressed which will prevent said printing. The connections 70 for bringing about this result include a key lever 14 on which said non-print key 13 is mounted, a link 15 extending upwardly from said key lever so that when said key lever is depressed, said link draws on a bell 75 crank 16 to the opposite end of which is attached a link 17 which swings a stop 18 in front of the type guide 8 for preventing the printing of the type 7 on the platen 6. Said stop is in the form of a padded bar 19 piv- 80 otted at 20 to a lug 21 screwed to the segment 5, and the end of said stop 18 is pivoted at 22 to the link 17 in such a way that, though the stop 18 swings horizontally and the bell crank 16 swings vertically, the nec- 85 essary play will be allowed in the pivot 22. The stop 18 is so formed that the leather pad 19 on one side of it will lie against the flat face 23 of the type-guide 8, while the other padded face will receive the impact 90 of the type-bar at about the height of the top of the segment.

As is most easily seen in Fig. 2, the type 7 are arrested at such a point that they can- 95 not possibly throw the ribbon against the platen, but yet they swing rearwardly far enough to operate the universal bar 10. The stop bar 18, as shown in dotted lines in Fig. 1, normally lies extending diagonally for- 100 ward from the segment toward the front of the machine where it lies beneath the frame, but will swing clear of such mechanism as the ribbon spools and the type bars 4 at the end of the segment. The lever 14 of the non-print key 13 is normally held upward by 105 a spring 24 so that said stop 18 is normally in its ineffective position. When said non- print key 13 is depressed, it may be swung

forwardly around a pivot 25 by which it is attached to its key lever, so that a hook 26 forming an extension of its key-stem proper will catch under the comb 27 which serves as a guide for the key levers. When said hook is thus caught, the stop 18 is held in its effective position. The key-stem of the key 13 may be prevented from swinging too far out of line by means of a stop 28 formed in an extension of said key-stem, so that said stop will lie beyond the upturned end 29 of the key lever proper and limit the throw of said stem on said key lever. As will be best seen in Fig. 1, the centers 20 and 22 can never get into a straight line with the link 17, and thereby the stop 18 is prevented from ever getting locked in ineffective position. The hook 26 is so formed that when it catches beneath the comb 27, it holds said comb by its upturned end and therefore cannot be easily accidentally displaced. Said non-print key is easily released by merely pressing the top of the key rearwardly.

Variations may be resorted to within the scope of the invention, and portions of the improvements may be used without others.

Having thus described my invention, I claim:

1. A typewriting and computing machine comprising a key, a lever on which the key is pivoted, a comb guiding said lever, a latch forming an extension of said key adapted to lock said key in said comb, and a stop limiting the throw of said key.
2. A front-strike typewriting and computing machine comprising a platen and keys, type-bars for writing on said platen and operated by said keys, a segment in which said type-bars are mounted, a stop pivoted on said segment, a key for swinging said stop in front of said type-bars so as to arrest them as they approach the platen, and a spring normally holding said stop ineffective.
3. A front-strike typewriting and computing machine comprising a platen and keys, type-bars actuated by said keys for writing on said platen, a segment in which said type-bars are mounted, a type-guide for alining said type-bars as they approach the platen, a stop pivoted on said segment, a key for swinging said stop across said type-guide, and a spring normally holding said stop ineffective.
4. A front-strike typewriting and computing machine comprising a platen and keys, type-bars actuated by said keys for writing on said platen, a segment in which said type-bars are mounted, a type-guide for alining said type-bars as they approach the platen, a stop pivoted on said segment, a key for swinging said stop across said type-guide,

and a spring normally holding said stop ineffective.

5. A typewriting and computing machine 65 comprising a platen and keys forming a keyboard, type-bars actuated by said keys for writing on said platen, a stop interposable to arrest said type-bars before the type strike the platen, a key at the keyboard for 70 moving said stop to its effective position, a spring normally holding said stop ineffective, and a latch operable by said key for holding said stop effective.

6. A typewriting and computing machine 75 comprising the combination with keys and a platen, of type-bars operated by said keys and comprising type for writing on said platen, a segment on which said type-bars are mounted, a type-guide mounted on said 80 segment, a stop movable between said type-guide and said type-bars at a point adjacent said segment for arresting said type before they strike the platen, and a key for operating said stop.

7. A typewriting and computing machine comprising the combination with keys and a platen, of type-bars operated by said keys and comprising type for writing on said platen, a segment on which said type-bars 90 are mounted, a type-guide mounted on said segment, a stop movable between said type-guide and said type-bars at a point adjacent to said segment for arresting said type before they strike the platen, a spring holding said 95 stop normally ineffective, and a key for moving it to effective position.

8. A typewriting and computing machine comprising the combination with keys and a platen, of type-bars operated by said keys 100 and comprising type for writing on said platen, a segment on which said type-bars are mounted, a type-guide mounted on said segment, a stop movable between said type-guide and said type-bars at a point adjacent 105 to said segment for arresting said type before they strike the platen, a spring holding said stop normally ineffective, a key for moving it to effective position, and a latch forming part of said key for holding said stop in its 110 effective position.

9. A front-strike combined typewriting and computing machine comprising the combination of a platen, type-bars, a segment in which the type-bars are mounted, a type 115 guide on said segment, a stop mounted on the segment, and a key to project said stop over the type guide in position to intercept the type-bars.
